UNITED STATES PATENT OFFICE

JOHN ALBERT CHOQUETTE, OF OTTAWA, ONTARIO, CANADA

AUXILIARY POWER MEANS FOR SHIPS AND THE LIKE

Application filed January 9, 1929. Serial No. 331,198.

This invention relates to improvements in auxiliary power means for ships and the like and is in part a continuation of my previously filed United States application No. 5 12,929 filed March 3, 1925 and gone to Patent No. 1,689,114 dated October 23, 1928.

One object of the invention is to provide means of durable and economical construction that will enable boats and the like to be 10 more efficiently driven.

Another object is to provide a method and means for creating within a vessel a head of the operating fluid in addition to the head automatically created in such fluid without 15 the vessel by the submerging of the vessel therein.

Yet another object is to provide auxiliary mechanism for accelerating the movement of ships and the like which will operate automatically on the vessel moving forward.

With the foregoing and other objects in view, hereinafter more fully referred to, the novel features of the invention comprise hydraulic power mechanism operable by pressure of the water in which a boat is partially submerged, and means within the vessel for diverting a portion of such water, causing it to circulate, and imparting to such portion additional pressure while in circulation to 30 co-operate with the water under normal pressure.

An example of my invention is illustrated in the accompanying drawings in which like numerals of reference indicate corresponding parts in each figure and in which,

Figure 1 is a side elevation of the mechanism in the hull of a ship which is partly broken away.

Figure 2 is a plan view of the underside 40 of a vessel partly broken away showing my invention.

Figure 3 is an enlarged section of the auxiliary power generating mechanism.

Figure 4 is an end view, partly in section, of Figure 3.

Referring more particularly to the drawings, A designates a vessel or boat of any suitable construction and B the turbines arranged in the bottom thereof and of special 50 construction as disclosed in my United States

application No. 748,404, filed November 7th, 1924, and gone to United States Patent No. 1,661,716, dated March 6, 1928, for improvements in fluid turbines, and in view of which it is not now proposed to enter into the details of the construction except in so far as 55 they affect the present invention.

The turbines B are provided with the usual rotor 10 mounted on the shaft 11 journaled in the ends 12. They are also provided with 60 inlet ports 13 and 14 and discharge ports 15 and 16.

The port 13 may be termed the main inlet port and communicates directly with the water in which the vessel is partially submerged through a suitably constructed opening 17 in the bottom 18 of the vessel A. Associated with this opening 17, and as more 65 particularly disclosed in Figure 3, is a scoop 19 of any suitable form rigidly secured at 20 in any suitable manner to the bottom 18.

This scoop is also provided at the front or intake end with a screen 21 and as a whole is adapted on the vessel A moving forward to scoop up the water and direct it through the opening 17 into the turbine intake port 13, a portion of the water so scooped up also being conveyed into the conduit or pipe 22 communicating with the opening 23 in the curved closed end of the scoop plate 19 and 70 hereinafter more fully referred to.

Connected in any well known manner to the discharge port 15 of the turbine B is a pipe 24 in turn connected to a pump 25 provided with a waste or exhaust pipe 26 having a control valve 27 and discharging 75 through the stern of the vessel.

The intake port 14 of the turbine is connected through a pipe 28 to a curved cross pipe 29 which in turn is connected through 80 a pipe 30 to a centrifugal pump 31, this pump being also connected through the pipe 22 to the source of water supply through the scoop 19 and is also provided with a control valve 32.

Connecting the pipe 28 adjacent to the intake port 14 with the intake 13 is an equalizer pipe 33.

The discharge port 16 is connected by a 100 pipe 34 and pipe 35 to the pipe 24 which in

turn, as previously described, is connected to the pump 25 provided with a controlled waste discharge pipe 26 whereby the waste or exhaust from the discharge ports is carried and conveyed without the vessel.

5 The opening 17 is provided with a closure slide 36 carried on the bottom 18 and operable through a rack 37 engaging with a toothed hand operated pinion 38.

10 The rate of revolution of the rotor 10 is dependent on the velocity and pressure of the operating fluid fed to the inlet ports from the auxiliary head formed in the pipes 28 and 29 and from the head formed through 15 the submerging of the vessel. To assist in increasing the velocity and cooperating with the head are the adjustable deflectors 42 fully described with the means for operating them in my previously issued United 20 States Patent No. 1,661,716.

Coming now to the essential and novel feature of my invention, namely the creation of an auxiliary head within the vessel for the operating fluid, I provide the pump 25 31 communicating through the pipe 22 with the scoop 19, the discharge side of this pump being connected through pipes 30, 29 and 28 with the intake port 14 of the turbines. In this way the fluid supplied on the forward 30 movement of the vessel is delivered under pressure by the pump 31 to the intake port 14 and a head of such fluid is maintained in the pipes 28, 29 and 30.

From the foregoing it will be understood 35 that in operation the intake ports 13 and 14 are first closed by means of the deflectors 42. The pump 31 is then started and as the vessel moves forwardly an auxiliary head is automatically formed in the pipes 28, 29 40 and 30 in addition to the head created by the submerging of the vessel. The deflectors are then opened and the operating fluid delivered to the intake ports 13 and 14 thereby materially increasing the velocity in revolution of the rotor 10 and providing automatically concentrated auxiliary power 45 means for the vessel.

As many changes could be made in the 50 above construction and many apparently widely different embodiments of my invention, within the scope of the claims, constructed without departing from the spirit or scope thereof, it is intended that all matter contained in the accompanying specification and drawings shall be interpreted as 55 illustrative and not in a limiting sense.

What I claim as my invention is:—

1. In a turbine of the character described, 60 the combination with a cylindrical casing provided with opposed fluid discharge ports and fluid inlet ports, of means for delivering a stream of fluid from without to the intake ports, and means for diverting a portion of 65 said stream and compressing it to create

a head prior to delivering the stream to said ports.

2. Auxiliary power means of the character described comprising a turbine provided with a casing having pairs of diametrically opposed intake and discharge ports, means for automatically delivering a stream of operating fluid under pressure to the intake ports on the vessel moving forward, means for simultaneously diverting a portion of such stream, subjecting such portion to the influence of pressure generating means, and delivering same to the intake ports. 70

3. Auxiliary power mechanism of the character described for ships and the like comprising in combination, a turbine, propellers operable by the turbine, means formed in the ship for delivering a stream of fluid to the turbine from without on the vessel moving forward, a centrifugal pump, controlled means connecting the fluid supply with the suction end of said pump, a plurality of controlled pipes of varying diameter connecting the discharge end of the pump with the turbine whereby a stream of operating fluid under ordinary and auxiliary pressure is provided, and means for discharging and exhausting the operating fluid. 80

In witness whereof I have hereunto set 85 my hand.

JOHN ALBERT CHOQUETTE.
